UNITED STATES PATENT OFFICE.

RALPH P. FOX, OF HARRISBURG, PENNSYLVANIA.

MOORING MEANS FOR AIRSHIPS.

Original application filed March 6, 1926, Serial No. 92,827. Divided and this application filed August 10, 1926. Serial No. 198,436.

The object of this invention is to provide particular means for mooring an airship of the dirigible type to a mast or plurality of masts,—this case constituting a division of 5 my application for patent filed March 6, 1926, Serial No. 92,827.

A further object is to provide, in connection with a mast to which the nose portion of the vessel may be secured, a second mast so 10 positioned that it may be engaged by a cable extending from either side of the air craft, at a point forwardly of the stern, and further to provide an intermediate structure by means of which access may be obtained to the interior 15 of the ship, when moored in the manner indicated.

A further object is to provide, in connection with mooring means for the nose portion, a plurality of cables extending from winding 20 devices within the structure to points on the sides of the main structure, forwardly of the stern, and means thru which the cables pass to prevent injury to the latter, incident to engagement with a stationary object, such as 25 one of the masts.

A further object is to provide in connection with cables, mounted as indicated, and adapted to be carried by the air craft, other cables to which the cables first named are adapted to 30 be connected, the second named cables extending upwardly thru the masts and over pulleys or the like at the top of each mast, the lower ends of the second named cables being accessible 35 from the ground, these cables being payed out, as occasion may require in connection with the mooring operation, or in connection with the release of the vessel.

With the foregoing and other objects in view, the invention consists in the novel construction and arrangement of elements described, illustrated and claimed, it being understood that modifications may be made within the scope of the claims without departing 40 from the spirit of the invention.

45 In the drawings forming part of this application,

Figure 1 is a view of the complete structure so far as the stationary elements are concerned, the air craft being shown somewhat 50 conventionally, but the latter being of the general type illustrated in the application above referred to.

55 Figure 2 is a plan view of the structure of Figure 1, and showing especially the use of the rear mooring cable at each side of the ma-

chine, so that connection may be effected with a rear mooring mast, it being assumed that the vessel may come into position with reference to the mast on either side thereof, as circumstances may determine. 60

Figure 3 is a view in elevation, with a portion in vertical section, showing the forward portion of the machine.

Figure 4 is a vertical transverse section on line 4—4 of Figure 2, showing especially the 65 relative position of the rear mooring cables.

Figure 5 is a detail in section, showing one 70 of the drums on which the cables are to be wound, the drums being controlled in part by ratchet mechanism at one end, and by a band brake at the other end thereof.

Figure 6 is a section on line 6—6 of Figure 5, this view showing the ratchet mechanism including a weighted pawl adapted to be retained in operative or inoperative position in 75 view of the position of the weight and the point of pivotal mounting of the pawl or ball.

Figure 7 shows the band brake, and the view constitutes a section on line 7—7 of 80 Figure 5.

Figure 8 is a detail view showing one of the pulleys over which the cable for each mast passes, the pulley being carried by a swiveled bracket including a central tubular portion.

Figure 9 is a section on line 9—9 of Figure 85 8.

The main portion of the machine includes the structure 10, and the suspended keel and gondola structure 11 and 12, propellers being illustrated at 13, and the stern structure 14 90 carrying vertical blade 15 and horizontal blade or elevator 16.

A forward mooring mast is designated 18 and includes a main structure, a base 19, and a platform 20 surrounded by a railing 21, 95 for the protection of those assisting in the mooring or releasing operations. Carried by each mast is a swiveled bracket 23 including a tubular portion 24, the bracket being mounted in ball bearings as indicated at 25, 100 and a flanged annular element 26 serving to retain the bracket in a position centrally of the mast, permitting the cable 28 to pass downwardly and pass thence thru a lower opening and outwardly over the base, where 105 the lower end may be coiled on the surface of the ground.

The cable 28 passes over upper pulley wheel 29 mounted in bracket 23, and has connection with a hook or other engaging device 30 110

adapted to make connection with a heavy ring 32.

The ring 32 is carried by one end of the forward mooring cable 33, and the latter extends downwardly below the nose portion 34 of the air craft and thru a channeled guiding and protecting member 35. Suitable winding means, controlled either manually or by power operated means are provided for 10 each mooring cable.

A rear mooring mast 38 is equipped in the same manner as the mast first described, and it is so positioned that for an air craft of a given size, the vessel will, when moored at 15 the nose portion in the manner indicated in Figure 1, come to rest, or be brought to anchoring position alongside of mast 38, the latter being forwardly of the stern and rudder construction, so that danger of injury 20 to the latter may be avoided.

Between the forward and rear masts is a stationary structure including a platform 40, a supporting portion 41, and an inclined portion 42, this structure as a whole affording 25 access to a main door 44 serving as an entrance to the interior of the aircraft.

An important feature is that a plurality of rear mooring cables 46 and 47 are provided, there being but one rear mooring 30 mast, and either cable 46 or 47 may be brought into use, as circumstances may determine. These cables 46 and 47 are each provided with a heavy ring such as 48 at the outer end, and the cables 33, 46, and 47 each 35 pass thru a cable guiding element or eye portion of heavy construction and illustrated at 49. Channel elements or curved tubes 50 and 51 extend around the sides of the lower portion of the structure 10, and protect the cables 46 and 47 from injury, and these 40 cables are controlled by winding and paying out devices of a type similar to that employed for the forward mooring cable 33.

The cables 33, 46, 47 may be wound on a 45 drum of the type shown in Figure 5 and elsewhere, the drum 55 being rigid with shaft or axle 56 operated by means of a crank 57, or thru gear wheel 58.

Cooperating with bracket wheel 59 rigid 50 with axle 56 is a dog 60, pivoted at 61, and weighted as shown at 62, so that the dog will be retained either in engaging position, as indicated in full lines in Figure 6, or in release position as shown in dotted line in Figure 6, a stop 63 serving an obvious purpose.

When the dog or pawl 60 is thrown out, and particular maneuvering is resorted to, in effecting a proper position, the brake of Figures 5 and 7 may be made use of, this brake 60 including a band 64 tightened by means of element 65 connected with the ends of the band and controlled by hand lever 66. The brake wheel is shown at 67, and the paying out of the cable may be controlled in an obvious manner.

When mooring the vessel, the cable 33 will be released, and allowed to pay out, by the weight of the heavy ring 32, and the accumulated weight of the suspended cable as the drum unwinds, and the cable carried by the mast may be released from a cleat or the like shown at 28', and the upper end of the cable 28 allowed to drop downwardly to a point at or near the surface of the ground, so that connection may be effected between hook 30 and ring 32. The cables may then be manipulated as required, in order to secure the vessel in about the position of Figure 1.

Having described the invention what is claimed is:—

1. In a device of the class described, a cable for mooring an air craft, devices for winding, retaining and releasing the cable, and a channeled guard mounted on and extending partly around the hull of the craft, the cable passing thru the guard and being protected thereby.

2. In a device of the class described, a cable for mooring an air craft, an apertured element on the hull of the craft thru which the cable passes, a channeled guard extending from the apertured element to a point on the lower side of the hull, and devices for winding and retaining the cable.

3. In a device of the class described, a cable for mooring an air craft, an apertured element on the hull of the craft thru which the cable passes, a channeled guard extending from the apertured element to a point on the lower side of the hull, and devices for winding and retaining the cable, the retaining device including a gravity controlled dog and a toothed device, the dog maintaining an engaging or release position with reference to the toothed device.

4. In a device of the class described, a plurality of cables for retaining an air craft, one of the cables being loosely connected with the nose portion of the craft, retaining means for this cable, and devices for mounting and retaining the other cable and effecting engagement with the craft, partly around the hull thereof and between the side and the lower portion of the hull of the craft, at a point forward of the stern thereof.

5. In a device of the class described, a plurality of cables for retaining an air craft, one of the cables being loosely connected with the nose portion of the craft, retaining means for this cable, and devices for mounting and retaining the other cables on opposite sides of the lower portion of the hull of the craft, at a point forward of the stern thereof, and channeled devices for protecting the cables, these devices last named extending partly around the surface of the hull being secured thereto.

6. The combination of a plurality of masts for an air craft, cables connected respectively with the nose portion of the craft and the lower portion of the hull on opposite sides

thereof and forwardly of the stern, the cables last named being adapted respectively for connection with one of the masts on either side thereof when the cable at the nose portion is connected with the other mast.

7. The combination of a plurality of masts for mooring an air craft, cables extending downwardly thru the masts, means for securing the cables at the base of the masts, cables 10 carried by the craft, at the nose portion thereof and on opposite sides of the hull forwardly of the stern, and means for winding, retaining, and releasing the cables last named, these cables being adapted for detachable connection with the cables first named.

8. The combination of a plurality of masts for mooring an air craft, tubular swiveled cable guiding means each including a pulley wheel, carried by the masts, cables extending downwardly thru the masts, means for securing the cables at the base of the masts, cables carried by the craft, at the nose portion thereof and on opposite sides of the hull forwardly of the stern, and means for winding, retaining, and releasing the cables last named, these 25 cables being adapted for detachable connection with the cables first named.

In testimony whereof I affix my signature.

RALPH P. FOX.
